HITCHING POST CAP OR SIMILAR ARTICLE

Lewis E. Peters, Beverly Shores, Ind.

Application April 15, 1954, Serial No. 30,037

Term of patent 14 years

(Cl. D38—8)

Figure 1 is a front elevational view of a hitching post cap, showing my new design;

Figure 2 is a front elevational view thereof;

Figure 3 is a rear elevational view thereof; and

Figure 4 is a top plan view thereof.

I claim:

The ornamental design for a hitching post cap or similar article, as shown.
